GARMENT HANGER

James W. Eaton, Chicago, Ill.

Application October 30, 1946, Serial No. 706,641

9 Claims. (Cl. 223—91)

1

The present invention relates to improvements in garment hangers.

More particularly, the present invention relates to hangers of the type for supporting clothes such as men's trousers, women's skirts or other garments and also adapted for supporting coats or the like.

An object of the present invention is to provide a hanger having a firm grip which hanger is readily manipulatable either to perform its gripping relationship or to be released from such gripping relationship.

A further object is to provide an improved hanger for trousers, skirts or the like, having releasable means for holding coats.

A further object is to provide an improved hanger which is simple and sturdy and well adapted to perform its functions.

A further object is to provide an improved hanger which is readily adaptable for manufacture on a mass production basis and which may be packed and shipped in a minimum of space.

A further object is to provide a hanger which is cheap to manufacture but efficient in service.

A further object is to provide an improved hanger for trousers, skirts or the like which is readily adaptable for the addition of simple and sturdy means for supporting coats or the like.

A further object is to provide a hanger well adapted to meet the needs of ordinary usage.

Further objects will appear as the description proceeds.

Referring to the drawings, Figure 1 is a view in side elevation of one embodiment of the present invention;

Figure 2 is a view in rear elevation of the structure shown in Figure 1;

Figure 3 is a view of the interior of the rear portion of the hanger, said view being taken along the plane indicated by the arrows 3—3 of Figure 6;

Figure 4 is a sectional view on an enlarged scale taken along the plane indicated by the arrows 4—4 in Figure 2;

Figure 5 is a top plan view of the structure illustrated in Figures 1 and 2;

Figure 6 is a sectional view taken along the plane indicated by the arrows 6—6 in Figure 1; and

Figure 7 is a view similar to Figure 6 but illustrating the structure in non-clamping position.

The illustrated embodiment of the present invention includes two clamping members 10 and 11, of which the clamping member 10 will be referred to as the front clamping member and the

2

clamping member 11 will be referred to as the rear clamping member. Said clamping members 10 and 11 are swung about a common axis provided by a straight pin portion 12 which forms part of a hook member 13. Said hook member 13 may be of relatively stiff wire. In the illustrated embodiment of the present invention, the two clamping members 10 and 11 are shown as being of substantially the same conformation, though their identity of conformation is not necessary in the broader aspects of the invention. However, it is desirable from a manufacturing standpoint that said clamping members 10 and 11 be substantially identical, the slight differences in said members being made therein from blanks which may be turned out from the same set of dies.

The clamping members 10 and 11 may be advantageously made of lightweight metal, stamped from the same set of dies. Each of the clamping members 10 and 11 is provided with the vertically disposed portion 14 and with the cross bar 15. Each clamping member 10, 11 is cupped out, a construction which will be clear from the drawings and the top part of each portion 14 is provided with a pair of bearing portions 16, 16 everted for receiving the straight pin portion 12 of the hook member 13. One bearing portion 16 on each upright portion 14 may be swaged inwardly in the direction of the axis of the pin portion 12, whereby the two clamping members 10, 11 may be symmetrically disposed with respect to each other. Said hook member 13 is provided with the portion 17 disposed in substantially right angular relationship with the pin portion 12. The other end of the pin portion 12 is provided with a washer 18, one side of which engages a side of the upright portion 14, the other side of which abuts against the riveted end of said pin portion 12. Said upright portion 14 and the washer 18 prevent the front and rear clamping members 10, 11 from spreading in a direction parallel with the axis of the pin portion 12.

The front and rear clamping members 10, 11 are urged apart by the spring 19, the mid-portion of which is coiled around the pin portion 12. One of the extremities of the spring 19 engages against the inner surface of the front clamping member 10 and the other extremity of said spring 50 engages against the inner surface of rear clamping member 11.

Means are provided for holding the front and rear clamping members 10, 11 in operative clamping relationship with each other. Such means include an elongated strut member 20

which may be formed by a wire, one extremity of which is coiled around the pin portion 12 of the hook 13 and the other extremity of which is held within a swedged strap portion 21 located adjacent to the bottom of the rear clamping member 11. A link 22 is provided, having a loop 23 encircling the strut 20 (Figure 3), having the portion 24 extending through the opening 25 in the front clamping member 10. The forward extremity of said link is reversely bent as indicated by the numeral 26. Said reversely bent portion 26 lies in co-planar relationship with the portion 24 of the link and assures that the link 22 will not turn and that the loop 23 will not get into jamming relationship with the strut 20 as said loop slides along said strut. The bent portion indicated by the numeral 27 between the portion 24 and the portion 26 of the link 22 has secured thereto a cup-shaped handle member 28. Said cup-shaped handle member 28 may be swedged out of sheet metal and is grooved on its outer surface midway of its width for receiving the bent portion 27 of the link 22. The lower edge 29 of the cup-shaped member 28 is adapted to engage in teeth 30, 30 located on both sides of the slot 25 in the front gripping member 10. The cup-shaped member 28 is provided with the upstanding lip 30a which insures that said cup-shaped member 28 will clear the teeth 30, 30 when said member 28 is moved upwardly. In other words, the front clamping member 10 and the strut member 20 form abutments for the link 22, one of which abutments being provided with teeth with which the link may engage for holding the clamping members in a plurality of clamping positions.

The horizontal extending crossbars 15, 15 of the front and rear clamping members 10 and 11 provide channels opening toward each other for the reception of elastic pads 31, 31 which is illustrated in Figure 4 extending beyond the boundaries of the channels in said portions 15, 15.

The outer wall of each of the channel-shaped crossbars 15, 15 is provided with a longitudinal extending rib 32. The ribs 32 in the rear clamping member 11 are utilized for the reception of extremities of coat supporting members 33, 33. Each of the coat supporting members 33 may be made of relatively stiff wire. As illustrated, each of the members 33 is provided with the mid-portion 34 for supporting a side of the shoulder portion of a coat. Each member 33 at one of its extremities is bent downwardly as indicated by the numeral 35 and then slanted as indicated by the numeral 36 (Figure 2). The other extremity of each member 33 is bent into substantial parallelism with the crossbars 15, 15 as indicated by the numeral 37. The inner extremity of the portion 37 is crimped upwardly slightly as indicated by the numeral 38 and the corresponding end portion 39 of the member 33 is disposed in parallel relationship with the portion 37.

The slanting end portion 36 of each member 33 is adapted to be inserted through an aperture in the side wall of the upstanding portion 14 of the rear clamping member 11. Said slanting portion 36 is inserted under a corresponding strap portion 40 struck out from the back wall of said rear clamping member 11. Each member 33 will be given a natural bias tending to thrust the end portion thereof into the corresponding crossbar 15 so that when the ends 36 and 39 thereof have been inserted into the rear gripping member 11, said member 33 will be resiliently held therein.

The present invention has the advantage that the front and rear gripping members 10, 11 are fundamentally alike in contours and dimensions and may be struck from the same set of dies. The front gripping member 10 will be provided with the slot 25 and the teeth 30. The rear clamping member 11 will be provided with the swedged straps 21 and 40, 40 together with the apertures for receiving the ends 36 and 39 of the members 33.

The device may be readily manipulated with the hook mounted upon a support. In order to release the gripping relationship between the clamping members 10, 11, it is necessary only to move the cup-shaped member 28 upwardly with the flip of a finger, thereby releasing the edge 29 from the teeth 30, 30. The spring 19 will force the two clamping members apart. In restoring the device to clamping relationship while the hook member 13 is being supported, it is necessary only to press the front clamping member 10 toward the rear clamping member 11. This will cause the link 22 to descend along the strut 20 carrying the cup-shaped member 28 with it. The strut 20 will be shaped to give a gradual tightening effect and the cup-shaped member 28 will be locked in any position corresponding to the relationship between the gripping members 10, 11; the edge 29 of said cup-shaped member entering into and being held in one of the grooves between the teeth 30, 30.

By reason of the fact that the coat hanger members 33, 33 are readily movable and replaceable, the device may be alternatively used as a hanger for trousers, skirts or the like or as a combined hanger for such articles together with a coat. If preferred, each of the members 33 may be provided with a depressed portion 40 as indicated in broken lines in Figures 1, 2 and 3 for holding the straps of ladies' evening gowns.

Though a preferred embodiment of the present invention has been described in detail, many modifications will occur to those skilled in the art. It is intended to cover all such modifications that fall within the scope of the appended claims.

What is claimed is:

1. In a hanger, in combination, a pair of clamping members swung about a common axis, means for biasing said clamping members apart, one of said clamping members being provided with a strut disposed in a plane at right angles to said axis, and link means looped around and slidable on said strut for locking said clamping members in clamping relationship with each other, said link means being provided with means co-operating with the other of said clamping members for preventing said link means from jamming on said strut.
2. In a hanger, in combination, a pair of clamping members swung about a common axis, one of said clamping members being provided with a strut located in a plane substantially at right angles to said axis, the other of said clamping members having a slot in substantially the same plane as said strut and a link looped around said strut and slidable in said slot, said link being provided with a gripping member for engaging the outer surface of said slotted clamping member for releasably holding said clamping members in clamping relationship with each other.
3. In a hanger, in combination, a pair of clamping members swung about a common axis, means for biasing said clamping members apart, one of said clamping members being provided

with a strut disposed in a plane at right angles to said axis and link means slidable on said strut for locking said clamping members in clamping relationship with each other, said strut being inclined relative to its clamping member, being closer thereto adjacent to the swinging edge of said clamping member than at regions adjacent to said axis.

4. In a hanger, in combination, a pair of clamping members swung about a common axis, one of said clamping members being provided with a strut located in a plane substantially at right angles to said axis, the other of said clamping members having a slot in substantially the same plane as said strut and a link looped around said strut and slidable in said slot, said link being provided with a gripping member for engaging the outer surface of said slotted clamping member for releasably holding said clamping members in clamping relationship with each other, said strut being inclined relative to its clamping member, being closer thereto adjacent to the swinging edge of said clamping member than at regions adjacent to said axis.

5. In a hanger, in combination, a rear clamping member, a front clamping member, a hook member having a straight portion forming an axis for swingingly mounting said clamping members, spring means for urging said clamping members apart, a strut carried by said portion of said hook member and secured to said rear clamping member, said strut lying in a plane substantially at right angles to said axis, said front clamping member being provided with a slot aligned with said strut, and a link having a portion encircling said strut, said link extending through said slot, the outer surface of said forward clamping member being provided with teeth, said link having means adapted to engage said teeth for holding said clamping members in a plurality of clamping positions.

6. In a hanger, in combination, a rear clamping member, a front clamping member, a hook member having a straight portion forming an axis for swingingly mounting said clamping members, spring means for urging said clamping members apart, a strut carried by said portion of said hook member and secured to said rear clamping member, said strut lying in a plane substantially at right angles to said axis, said front clamping member being provided with a slot aligned with said strut, and a link having a portion encircling said strut, said link extending through said slot, the outer surface of said forward clamping member being provided with teeth, said link having means adapted to engage said teeth for holding said clamping members in a plurality of clamping positions, said strut being inclined relative to its clamping member, being closer thereto adjacent to the swinging edge of said clamping member than at regions adjacent to said axis.

7. In a hanger, in combination, a pair of clamping members swung about a common axis,

means for biasing said clamping members apart, one of said clamping members being provided with a strut disposed in a plane at right angles to said axis, link means looped around said strut and slidable thereon, said other clamping member having a slot for slidably receiving said link means, said link means being provided with a gripping member for engaging the outer surface of said slotted clamping member for releasably holding said clamping members in clamping relationship with each other, said link means having a portion co-operating with the sides of said slot for preventing jamming of said link means upon said strut.

8. In a hanger, in combination, a pair of clamping members swung about a common axis, means for biasing said clamping members apart, one of said clamping members being provided with a strut disposed in a plane at right angles to said axis, link means looped around said strut and slidable thereon, said other clamping member having a slot for slidably receiving said link means, said link means being provided with a gripping member for engaging the outer surface of said slotted clamping member for releasably holding said clamping members in clamping relationship with each other, said link means having a portion co-operating with the sides of said slot for preventing jamming of said link means upon said strut, said strut being inclined relative to its clamping member, being closer thereto adjacent to the swinging edge of said clamping member than at regions adjacent to said axis.

9. In a hanger, in combination, a rear clamping member, a front clamping member, a hook member having a straight portion forming an axis for swingingly mounting said clamping members, spring means for urging said clamping members apart, a strut carried by said portion of said hook member and secured to said rear clamping member, said strut lying in a plane substantially at right angles to said axis, said front clamping member being provided with a slot aligned with said strut, and a link having a portion encircling said strut, said link extending through said slot, said strut and said front clamping member forming abutments for said link, one of said abutments being provided with teeth, said link having means adapted to engage said teeth for holding said clamping members in a plurality of clamping positions.
